UNITED STATES PATENT OFFICE.

FRED SCHELP, JR., OF BALLWIN, MISSOURI, ASSIGNOR OF ONE-HALF TO
GEORGE H. SCHELP, OF SAME PLACE.

VEHICLE-SPRING.

SPECIFICATION forming part of Letters Patent No. 339,588, dated April 6, 1886.

Application filed November 16, 1885. Serial No. 182,965. (No model.)

To all whom it may concern:

Be it known that I, FRED SCHELP, Jr., of Ballwin, St. Louis county, Missouri, have made a new and useful Improvement in Vehicle-Springs, of which the following is a full, 5 clear, and exact description.

The improvement consists in the employment of two springs whose inner ends lap and are attached to the body or the spring-bar of the 10 vehicle, and whose outer ends extend in opposite directions and are respectively attached to opposite ends of the vehicle-axle, and preferably upon opposite sides of the axle.

The annexed drawings, making part of this 15 specification, exhibit the most approved mode of carrying out the improvement.

Figure 1 is a bottom view of so much of the 20 vehicle as is necessary to an understanding of the improvement, and Fig. 2 is a view in perspective looking from beneath of the spring as attached in place.

The same letters of reference denote the same parts.

A represents the vehicle-body. B B represent the vehicle-axles, and C C' represent the 25 boards, plates, and bars to which the upper or inner ends of the springs are more immediately attached, all of which parts are of the customary forms.

D D represent the two springs which connect the vehicle-body, or the boards, plates, or bars C C' of the vehicle-body, with the axle. 30 Their inner ends, d d, respectively, not only lap, but preferably extend sufficiently past each other to bring the points of attachment of the ends d d well toward the opposite sides of the vehicle-body, or, what is the same thing, well toward the opposite ends, respectively, of the board, plate, or bar C. The springs D D 35 thence extend in opposite directions, and

by means of suitable and well-known modes of attachment are connected with the vehicle-axle B well toward the opposite end thereof, and preferably, and as shown, upon opposite sides, respectively, of the axle. In this manner a very long spring can be used to support the vehicle-body. A similar pair of the springs D D can be used at each end of the vehicle-body—that is, the springs D D can be used at either or both ends of the vehicle-body, 45 as desired. I also desire not to be limited to springs whose inner ends, d d, lap at their point of attachment to the vehicle-body, as in some instances—as in wide-track vehicles—the springs need not lap at their point of attachment. 50

I claim—

1. The herein-described springs D D, whose inner ends lap and are attached to the body or the spring-bar of the vehicle, and whose outer 60 ends extend in opposite directions and are respectively attached to opposite ends and respectively upon opposite sides of the axle.

2. The herein-described springs D D, whose inner ends lap and are attached to the vehicle-body, or to some part of the body well toward opposite sides, respectively, of the body, and whose outer ends extend in opposite directions, respectively, and are respectively attached to opposite ends and respectively upon 65 opposite sides of the axle.

3. The springs D D, attached to the axle B upon opposite sides and toward opposite ends, respectively, of the axle, and at their upper ends supporting the vehicle-body at opposite 70 sides, respectively, thereof.

FRED SCHELP, JR.
